US00D923590S

(12) **United States Design Patent** (10) **Patent No.:** **US D923,590 S**
Lu (45) **Date of Patent:** **** Jun. 29, 2021**

(54) **SPEED CONTROL SWITCH OF AN ELECTRIC NAIL DRILL**

(71) Applicant: **SHENZHEN XPADSP TECHNOLOGY CO., LTD.**, Shenzhen (CN)

(72) Inventor: **Qing Lu**, Shenzhen (CN)

(73) Assignee: **SHENZHEN XPADSP TECHNOLOGY CO., LTD.**, Shenzhen (CN)

(**) Term: **15 Years**

(21) Appl. No.: **29/736,706**

(22) Filed: **Jun. 2, 2020**

(51) LOC (13) Cl. **13-03**

(52) U.S. Cl.

USPC **D13/168**

(58) **Field of Classification Search**

USPC D13/137.3, 168, 171; D14/155, 188, D14/205, 217, 218, 225, 255, 240, 433; D21/566; D10/104.1, 106.1

(57) **CLAIM**

The ornamental design for a speed control switch of an electric nail drill, as shown and described.

DESCRIPTION

FIG. 1 is a front elevational view of a speed control switch of an electric nail drill showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines in the drawings depict portions of the speed control switch of an electric nail drill that form no part of the claim.

1 Claim, 4 Drawing Sheets
